UNITED STATES PATENT OFFICE.

ONEY BURY AND JAMES ALBERT MASON, OF HOUSTON, TEXAS.

CAMPER'S OUTFIT CHEST.

Application filed February 12, 1923. Serial No. 618,522.

To all whom it may concern:

Be it known that we, ONEY BURY and JAMES ALBERT MASON, J. A. MASON being a citizen of England and O. BURY a citizen of the United States, residing at Houston, in the county of Harris and State of Texas, have invented certain new and useful Improvements in Campers' Outfit Chests, of which the following is a specification, reference being had to the accompanying drawings.

This invention relates to campers' outfits, and has for its object to provide a device of this character wherein a combination chest and camp furniture is provided, the form of the chest being eliminated when the furniture is used and the form of the furniture eliminated when the chest is used.

It is a further object of the invention to provide a device of this character wherein a foldable table and benches are provided and so constructed that they may be interengaged to provide a chest for the reception of cooking utensils and like articles used by campers.

It is still a further object of the invention to provide a device of this character including seats and a foldable table, the seats being arranged to provide the frame of a chest and the table arranged to provide the sides and ends of the chest.

It is also an object of the invention to provide a device of this character wherein the seat of one bench serves as the bottom of the chest and the seat of the remaining bench as a top for the chest.

With these and other objects in view, the invention consists in the improved construction and arrangement of parts to be hereinbelow more particularly described, fully claimed and illustrated in the accompanying drawings, in which:—

Figure 1 is a perspective view of a combination campers' outfit showing the furniture when used to form the chest, the bench having the movable seat being partially raised from the remaining portion of the chest;

Figure 2 is a transverse sectional view of the chest;

Figure 3 is a perspective view of the bench used to provide the bottom of the chest;

Figure 4 is a perspective view of the bench used to provide a top for the chest; and

Figure 5 is a perspective view of the table in its extended position.

This invention provides means whereby a chest may be formed of a size capable of being supported upon the running board of an automobile or conveniently transported by campers, hunters or picnic parties, and so arranged that when the party desires to use furniture such as a bench and a table the entire chest is disassembled and the various parts thereof used as benches and as a table.

In order to provide a structure of this character, there is provided a novel form of foldable table including sections 5, 6 and 7, the sections 5 and 7 being hinged as at 8 to the section 6. The sections 5 and 7 are also adapted to move toward each other. The section 5 is provided with a pair of supporting legs 9 which are secured to the end portions of said section inwardly of the edge of said end. These legs have their inner edges 10 longitudinally inclined to facilitate folding of the table. The legs are secured by any suitable means and braced by angle irons 11. The section 7 is likewise provided with a pair of legs 12, said legs being disposed inwardly of the edges of the section and having their forward longitudinal edges 13 inclined. These legs are secured by any suitable means and braced by angle irons 14.

It will be noted that the legs 9 and 12 are disposed a considerable distance inwardly of the longitudinal and end edges of their respective sections so as to facilitate folding of the table. Secured to the lower end portions of the central section 6 of the table are cleats 15. These cleats are disposed inwardly of the edges of said ends to provide a support for the end supporting members 16.

These members are intended to be engaged with the center section and secured to the cleats and cooperate with the legs 9 and 12 to provide proper supporting means for the table when extended. In this way each section is provided with supporting legs. In addition to this, the supporting members 16 correspond in length to the width of the center section 6 and in height to the length of the legs 9 and 12. The purpose of this is to provide end members for the chest to be

hereinafter described.

When the table is not in use, the sections 5 and 7 are moved toward each other so as to permit the legs 9 and 12 to move inwardly of

the end portions 16. The beveled edges 10 and 13 of the legs permit the same to overlap each other without contacting. The lower end portions of the sections 5 and 7 are intended when folded to engage the ends of the supporting member 16 of the section 6 to substantially provide a box which is used to form a portion of the chest.

In connection with the foldable table, 10 benches 17 and 18 are provided. The bench 17 comprises a frame including side members 19 and end members 20. Legs 21 are provided, the upper end portion of each leg being disposed inwardly of the frame in such 15 a way that the broad face of each leg engages the end members 20 of the frame, while the narrow face of each leg engages the side members of the frame. A seat 22 is secured to the frame.

20 The bench 18 comprises a frame including side members 24 and end members 25 which are secured to the side members. The end portions 26 of the side members 24 are mortised, said mortise coacting with the adjacent 25 end member 25 to provide a recess 27. Each of said recesses is intended to receive the upper end of a leg 28, the legs 28 corresponding in shape to the legs 21 of the bench 17, each leg being so disposed that the broad face 30 engages the inner wall of the recess, while the narrow edge portion of the leg engages the side wall of the recess. The purpose of this is to dispose the legs 28 substantially at right angles to the legs 21. A seat 29 is provided for the bench 18, said seat being hinged as at 30 to the frame of the bench to not only provide a seat for the bench but also a lid for the chest.

When the device is used by the camper 40 the sections 5, 6 and 7 of the table are extended outwardly and disposed in the same plane and supported by the legs 9 and 12, and the benches are positioned as desired, as they are not connected to the table. Furthermore, the 45 legs of each bench are stationary with respect to the frame and seat.

After the table and benches have been used and it is desired to fold the same, the bench 50 17 is inverted so that the legs 21 thereof extend upwardly. The bench 18 is then placed upon the bench 17 in such a way that the lower ends of the legs 28 of the bench engage the frame of the bench 17, the lower ends of the legs 21 being disposed in the frame of 55 the bench 18. In this way each leg 28 coacts with the adjacent leg 21 to provide a right angular corner member, said corner members coacting with each of the frames of the benches to provide a chest frame, the seat 22 60 of the bench 17 forming the bottom of the chest, while the seat 29 of the bench 18 provides a movable lid for the chest, in view of its hinged connection to the frame of the bench 18. The sections 5 and 7 of the table 65 are then swung toward each other and into

engagement with the ends of the supporting members 16. The box structure thus formed is then placed within the chest frame, the sections 5 and 7 forming the front and rear walls of the chest within the frame, while the 70 supporting members 16 form the end walls of the chest within the chest frame. This leaves a large space within the box structure of the folded table for the reception of any desired article. If desirable, a hasp may be placed on the edge of the seat 29 and a keeper on the side member 24 of the frame of the bench so as to lock the chest. This compact structure may then be placed on the running board of an automobile or in a small space 80 for transportation.

From the foregoing it will be readily seen that this invention provides a novel outfit especially adapted and desired by campers and tourists in view of the fact that each part of the device serves a double purpose, thus eliminating the necessity of a separate case for carrying not only the campers' utensils and accessories, but for carrying the campers' furniture and wherein the furniture is arranged to provide a chest. It will also be noted that the benches serve as a protection for the table as the table is disposed entirely within the chest frame formed by the benches, and as the legs of the benches are not movable, a very substantial structure is provided, capable of standing hard usage without danger of damage. This device may also be made in various sizes, for instance, in miniature form as a toy for children or in a 100 larger size as furniture for a child's play room, the larger sized furniture providing a "kiddies kit" when not in use in which toys may be stored. All of these features are possessed by a device which is composed of only 105 a small number of simple parts, the only movable members of the device being the hinged sections of the table and the seat of the bench 18.

What is claimed is:—

1. A device of the character described comprising a pair of benches including a supporting frame and legs, the seat of one of said benches being movable, one of said benches being inverted and adapted to support the remaining bench and to coact with said bench to provide a chest frame, the movable seat of the upper bench serving as a lid for the frame, and a foldable table disposed within the chest frame to provide 115 chest sides and ends.

2. A device of the character described embodying furniture and a chest comprising a pair of benches, the legs of one bench extending into the frame of the opposite bench, the seats of said benches being positioned in spaced relation to each other, the legs of each bench coacting to provide corner members, said corner members coacting with the frame of the bench to provide a chest frame, 130

and a foldable table including supporting legs and end sections, said sections being foldable upon certain of the end legs to provide front and rear walls for the chest, 5 said legs providing end walls for the chest.

3. A device of the character described comprising a pair of benches, each bench embodying a frame, legs secured to and depending from the frame, each of said 10 benches being provided with a seat, one of said seats being hinged to its frame, the remaining seat being secured to its frame, the last mentioned seat being adapted to provide a bottom member when inverted, the upwardly projecting legs of the inverted 15 bench being adapted to extend beneath the movable seat of the remaining bench and into the frame of said bench to coact with the legs of the first mentioned bench to provide a chest frame, and a table comprising 20 a center section, end sections hinged to the center section, end supporting members carried by the center section, supporting legs carried by each of the end sections, said 25 supporting legs being foldable within the end members of the center section upon movement of the end sections into engagement with the end members of the center section, said folded table being disposed within 30 the chest frame beneath the movable seat.

4. A device of the character described comprising a pair of benches each including a rectangular supporting frame and legs, one of said benches being adapted to be inverted for supporting the other bench in 35 upright position, the legs of the benches being arranged in a species of telescoped relation to define a chest frame, and a foldable table including hingedly connected sections 40 and legs hinged thereto, one section being

disposable upon the inverted bench, and other sections constituting sides for the chest, the intermediate supporting legs forming ends for the chest.

5. A device of the character described 45 comprising a pair of benches each including a rectangular supporting frame and legs, one of said benches being adapted to be inverted for supporting the other bench in upright position, the legs of the benches being arranged in a species of telescopic relation to define a chest frame, and a foldable table including hingedly connected sections and legs hinged thereto, one section being disposable upon the inverted bench and other 50 sections constituting sides for the chest, the intermediate supporting legs forming ends for the chest, the outermost legs having inclined edges and fitting together when folded against the intermediate legs.

6. A device of the character described 55 comprising a pair of benches each including a rectangular supporting frame and legs, one of said benches being adapted to be inverted for supporting the other bench in 60 upright position, the legs of the benches being arranged in a species of telescopic relation to define a chest frame, and a foldable table including hingedly connected sections and legs hinged thereto, one section being 65 disposable upon the inverted bench and other sections constituting sides for the chest, the intermediate supporting legs forming ends for the chest, the outermost legs having inclined edges and fitting together when folded against the intermediate legs.

In testimony whereof we hereunto affix our signatures.

ONEY BURY.
JAMES ALBERT MASON.
